PATENTED MAY 19, 1903.

T. W. HEERMANS.
CONTROLLING MECHANISM FOR ELEVATORS.

APPLICATION FILED NOV. 4, 1895.

NO MODEL.

UNITED STATES PATENT OFFICE.

THADDEUS W. HEERMANS, OF CHICAGO, ILLINOIS.

CONTROLLING MECHANISM FOR ELEVATORS.

SPECIFICATION forming part of Letters Patent No. 728,228, dated May 19, 1903.

Application filed November 4, 1895. Serial No. 567,885. (No model.)

To all whom it may concern:

Be it known that I, THADDEUS W. HEERMANS, a citizen of the United States, residing at Chicago, in the county of Cook and State of Illinois, have invented a new and useful Controlling Mechanism for Elevators, of which the following is a specification.

This invention relates to valve-controlling mechanism for elevators.

10 The object of the invention is to simplify and improve the construction of mechanism for controlling the valves of elevators and to render the same more positive and efficient in operation.

15 The invention consists, substantially, in the construction, combination, location, and relative arrangement of parts, all as will be more fully hereinafter set forth, as shown in the accompanying drawings, and finally 20 pointed out in the appended claims.

Reference is made to the accompanying drawings and to the views and reference-signs appearing thereon, wherein—

25 Figure 1 is a view in front elevation of an apparatus embodying my invention, parts being broken and parts in vertical section. Fig. 2 is a view in side elevation, parts being broken and parts in vertical section.

30 In the drawings, A designates a portion of the cage or car of an elevator structure adapted to travel up and down in the elevator well or shaft and to be propelled by any suitable motor, which it is not necessary to show.

35 B designates a cable of the class known in the art as a "running" cable and is attached to the car, as at C, to travel therewith. Mounted upon the car and suitably journaled is a drum D, around which one leg or run of the cable B is arranged to pass, as shown, and 40 said drum or other suitable or convenient operating device is or may be provided with an operating hand-wheel or other suitable device, as at E, by which cable B may be moved relatively to the car—that is, taken up and 45 paid out, as will presently be more fully described.

In the top of the elevator well or shaft is arranged a suitable bracket or support, as at F, to which is pivoted, as at a, intermediate 50 its ends, a lever G, having at one end an adjustable counterbalancing-weight H and pivotally secured at its opposite end, as at b, to

a suitable frame or plate, as K, upon which are journaled three guide-pulleys L, M, and O. The pulleys L and M are preferably arranged with their axes in the same horizontal plane, and, if desired, and preferably, all the pulleys L, M, and O are in the same vertical plane, though pulley O is journaled in the space between and in a lower horizontal 55 plane than pulleys L and M. To the center of frame or plate K is pivoted, as at c, one end of an arm or link P, the other end of said arm or link being pivoted, as at d, to bracket or support F. The length of arm or link P between its points of pivotal support c d is preferably the same as the distance between the 60 pivotal points b a of lever G. The purpose of this arrangement is to secure uniformity of movement of plate or frame K under the influence of the counterbalancing movement of weighted arm or lever G and to prevent said plate or frame from rocking about the 65 pivotal point b when power is applied from the car to cable B to effect an actuation of the 70 valve or controlling mechanism of the hoisting-motor, as will be readily understood by persons skilled in the art.

In the bottom of the elevator well or shaft are the traveling pulleys R S, arranged to be 80 supported by the bights of the cable B in a well-known manner, and attached to each pulley R S is a cable or other suitable flexible connection T V, leading to the valve or controlling mechanism of the hoisting-motor, 85 whereby when one or the other of said sheaves is raised or moved by the manipulation of the central device on the car the valve or controlling mechanism of the engine is correspondingly shifted or actuated in one direction or the other, as the case may be, and as 90 will be readily understood.

In order to guide the sheaves R S during their movements, and hence to prevent them from twisting or swinging loosely about, I provide the guides W Q, and I provide each sheave with a suitable bar J, arranged to engage the guides W Q. This result may be accomplished in any suitable or convenient manner, the form shown being a simple way 100 wherein the guides W Q are vertical brackets arranged in pairs, the bracket Q being centrally located and serving as one of the guides for both sheaves. A bar J is mounted on

both faces of each pulley R S, and the guides W Q are received between the projecting ends of said bars, as clearly shown.

The lead of the cable B is as follows: From 5 the point C where said cable is attached to the car it leads up over sheave L, thence over sheave M, thence down and around loose sheave S, thence to and around the drum D on the car, thence to and around sheave O, 10 thence down and around loose sheave R, and finally to point C, where it is secured to the car. The relative position of sheaves R and S corresponds with that of sheaves L and M, and hence it will be seen that the cable forms 15 two bights at the top and two at the bottom of the well, one bight at the top being arranged within the other bight, and hence the four runs or legs of the cable are vertically arranged and are not crossed, but extend in 20 straight vertical lines.

From the above description it will be observed that the cable is a single continuous rope and that it travels with the car. When the cable-operating device on the car is in its 25 normal position—that is, when it is at rest—the cable travels over the several sheaves or pulleys, and especially the loose sheaves or pulleys R and S, while the car is ascending or descending, without raising or lowering them, 30 and hence without effecting an actuation of the valve or control mechanism of the hoisting-motor. When, however, the conductor or attendant on the car actuates the cable-controlling device to take up and pay out the cable 35 relative to the motion of the car—that is, when he turns the wheel E in the direction of travel of the hands of a watch, for instance—that run or leg of the cable leading to drum D from sheave or pulley O is wound upon said drum, 40 and hence effects a raising of loose sheave or pulley R, carried in the bight of the cable formed by the two left-hand legs or runs, as shown in Fig. 1. The same movement causes the leg or run extending from drum D to 45 ward and around sheave or pulley S to be correspondingly paid out, thereby permitting said sheave or pulley to be lowered, and hence effecting an actuation of the hoisting-motor control or valve mechanism. In a similar manner a reverse movement of sheaves or pulleys R and S is effected by the operation 50 of the cable-controlling device on the car in the opposite direction.

It will be seen that by mounting all the pulleys in the top of the well upon a movable frame or bracket and counterbalancing said frame or bracket the slack in each separate run or leg of the cable is constantly and independently taken up and that each leg or 55 run is maintained taut, which result is not accomplished in the case where a single counterbalanced sheave is provided for the entire cable, and hence the valve-controlling mechanism of the hoisting-motor responds immediately and quickly to a slight range of movement of the cable-controlling device on the car. Moreover, as the runs or legs of the ca-

ble are not crossed, but extend directly vertical, the application of power to the cable-controlling device on the car is transmitted 70 to the valve or control mechanism of the hoisting-motor in a more direct and positive manner than would be the case otherwise. Again, by providing a plate or frame upon 75 which the pulleys L, M, and O are journaled handling, transportation, and erection of the apparatus are greatly facilitated, and hence the cost of the structure is greatly reduced, as it is unnecessary to provide any supports or journal-bearings in the framework of the 80 elevator-well except the bracket or support F.

It will be evident that many changes and alterations in the details of construction, size and proportions of parts, arrangement, and relative arrangement of parts would readily 85 suggest themselves to persons skilled in the art as occasion or the particular condition of each case may require and still fall within the spirit and scope of my invention. I do not desire, therefore, to be limited or restricted 90 to the exact details and form shown and described; but,

Having explained the object and nature of my invention and a form of apparatus embodying the same and having explained the 95 function and mode of operation thereof, what I claim as new and of my own invention, and desire to secure by Letters Patent of the United States, is—

1. In a controlling device for elevators, an 100 endless traveling cable having two pairs of bights formed therein, means for supporting one of said pairs of bights at the top of the elevator shaft or well, one of said bights being arranged between the runs forming the 105 other bight, an independent sheave or pulley loosely mounted in each member of the pairs of bights at the bottom of the shaft or well, an independent flexible connection from each 110 of said sheaves to the valve or controlling mechanism of the hoisting-motor, guides in which said independent sheaves operate, and means, carried by the car, arranged to engage one of the runs forming a part of a bight at each end of the shaft or well, for actuating 115 said cable; as and for the purpose set forth.

2. In a controlling device for elevators, a continuous traveling cable having bights formed therein at the top and bottom of the elevator-well, sheaves carried in the bights 120 at the bottom of the shaft, each having a pair of bars mounted on opposite faces thereof with projecting ends, stationary guides adapted to be received between the projected ends of each pair of said bars, means connected 125 with said sheaves for controlling the valve-gear of the hoist-motor and means carried by the car for taking up and paying out said cable, as and for the purpose set forth.

3. In a controlling device for elevators, a 130 cable, connections between the same and the motor-valve or control mechanism, means for actuating said cable from the car, guiding-sheaves arranged in the top of the elevator-

well, a supporting-plate therefor, a pivoted counterbalanced lever supporting said plate, and a link connection between said plate and a fixed part of the framework; as and for the 5 purpose set forth.

4. In a control device for elevators, a cable, connections between the same and the motor-valve or controlling mechanism, means for actuating said cable from the car, guiding- 10 sheaves for said cable arranged in the top of the elevator-well, a plate or frame upon which said sheaves are journaled, a stationary bracket, a lever pivoted intermediate its ends upon said bracket, and carrying a weight 15 at one end and pivotally supporting the said plate at the opposite end, and a link pivotally connected to said plate and bracket respectively; as and for the purpose set forth.
5. In a control device for elevators, a cable, 20 connections between the same and the valve

or control mechanism of the motor, means carried by the car for actuating said cable, a pair of guiding-sheaves arranged in the same horizontal plane and spaced a distance apart located in the top of the elevator shaft or well, 25 and adapted to receive said cable to form a bight, a third sheave arranged adjacent to but in a lower horizontal plane than said pair of sheaves, and adapted to receive said cable to form a second bight therein, a plate having bearing for all of said sheaves, means for pivotally supporting and counterbalancing said supporting-plate; as and for the purpose set forth.

In witness whereof I have hereunto set my 35 hand this 31st day of October, 1895.

THADDEUS W. HEERMANS.
